Primary Examiner — Randall Gholson(74) Attorney, Agent, or Firm — Perkins Coie LLP(57) CLAIM

The ornamental design for a panel for a leg guard, as shown and described.

DESCRIPTION

FIG. 1 is a front perspective view of a leg guard with a panel showing my new design; and,
 FIG. 2 is a side perspective view of a leg guard showing the design in FIG. 1.
 In the drawings, the broken lines depict environmental subject matter only and form no part of the claimed design.
